CLAIM

The ornamental design for a mousetrap, as shown and described.

DESCRIPTION

FIG. 1 is a perspective view showing the top and a side and the rear of the mousetrap;

FIG. 2 is a side elevation view of the mousetrap;

FIG. 3 is an opposite side elevation view of the mousetrap;

FIG. 4 is a front elevation view of the mousetrap;

FIG. 5 is a rear elevation view of the mousetrap;

FIG. 6 is a plan view of the top of the mousetrap,

FIG. 7 is a plan view of the bottom of the mousetrap; and,

FIG. 8 is a further perspective view showing the top, front and a side of the mousetrap.

The broken line showing of environment in the drawings is included for the purpose of illustrating only and forms no part of the claimed design.
